UNITED STATES PATENT OFFICE.

JAMES EDWARD SCHUMACHER, OF YORK, ENGLAND.

BRAKE FOR RAILWAY AND ROAD VEHICLES.

No. 893,660.

Specification of Letters Patent.

Patented July 21, 1908.

Application filed May 6, 1907. Serial No. 372,224.

To all whom it may concern:

Be it known that I, JAMES EDWARD SCHUMACHER, a subject of the King of Prussia, residing at 68 Vyner street, Haxby Road, 5 York, in the county of York, England, have invented new and useful Improvements in or Relating to Brakes for Railway and Road Vehicles, Gun-Carriages, Ammunition-Wagons, and the Like, of which the following is a 10 specification.

This invention relates to improvements in brakes which are applicable for use on railway rolling stock, road vehicles, such as carriages, cabs, drays, wagons, timber wagons, 15 which are frequently termed in England "Timber Cutts" and the like, gun carriages, ammunition wagons and the like, all of which are hereinafter termed and included in the term "the vehicle."

20 The object of this invention is to provide means so that the brake can either be applied by hand or be automatically drawn out or brought into action when, say, the vehicle is going up a hill or incline, or on the level, 25 and to be instantly thrown into action when it commences to descend, say, the hill or the incline. Means are also provided for securely locking the brake in or out of action by hand.

30 In the hereunto annexed drawings this invention is shown applied to a timber wagon, but I wish it to be clearly understood that this is to be taken as an example only, as it may be as readily applied to any of the here- 35 inbefore mentioned vehicles.

In the drawings:—Fig. 1. is a side elevation of timber wagon with a brake constructed according to this invention, and in which the brake is brought into operation by a 40 thrusting action. Fig. 2. a plan of same looking at the top. Fig. 3. a plan of same looking at the underside. Fig. 4. an enlarged part sectional elevation of a portion of the brake actuating mechanism. Fig. 5. 45 an enlarged part sectional elevation of same. Fig. 6. an enlarged elevation of levers for applying the brake by hand. Fig. 7. an enlarged elevation showing the levers locked when the brake is applied. Fig. 8. an elevation of lever for throwing the brake entirely 50 out of action. Fig. 9. an elevation of mechanism for operating the brake by a pulling action. Fig. 10. a plan of same.

Like parts in all the views are marked 55 with similar letters of reference.

In Fig. 1, the front and rear wheels A, B, are shown in dotted lines in order to show the brake actuating mechanism more clearly.

C is the shaft of the vehicle; E. F. the axles; D its under carriage; G the centerpole 60 provided with holes g whereby the rear portion H may be adjusted nearer to and further from the under carriage D and retained in position by a bolt or pin h.

I, J, are detachable pins employed for 65 keeping the timber in position which is laid on the top of the rear portion H and the front portion K. The front portion is attached by stay L to the center pole G. The center pole is also jointed at M to the under- 70 carriage D.

N are the brake blocks attached to the cross piece O suspended from the center pole G by a casting P arranged to slide thereon.

To the undersurface of the center pole G is 75 carried in suitable bearings,—fixed to the center pole,—so as to slide freely, a drawbar Q. The drawbar is made in two widths, its rear end q being the narrowest, and also provided with tapering edges to form a vee slide 80 as shown at Fig. 5. The drawbar is also connected by a link R to a double ended bar S, which, in plan is bifurcated. The bar S is carried in bearings U¹, fixed to the under carriage D, and its bifurcated ends are attached 85 to the bolt or pin T to which the shafts are also connected. The bar S is also provided with a boss s for receiving the attaching bolt s¹ by which the bar S and one end of the link R are attached together. The opposite end 90 of the link is jointed by a pin or screw r to the widest end of the drawbar Q. Fixed or adjustable stops may, if so desired, but not necessarily so, be provided on the under surface of the bar S and made to impinge against the 95 ends of the bearings U¹ when the drawbar Q is in its extreme outward position.

In order to provide for the varying position of the rear wheels B and portion H, the cross piece O to which the brake blocks N are 100 fixed, is connected to the end q by the sliding block V from which a screw threaded pin W pendently projects. On the pin W a nut or hand wheel X is made to work for clamping or fixing the cross piece O and slide V to the 105 drawbar.

To the rear portion H is fixed bearings Y in which is mounted a shaft Z. At a suitable distance from the inner end of the said shaft is mounted a lever 1 which is connected by a 110

bar 2 with a bifurcated end 4 to the pin W and slide V and retained in position by the hand wheel X.

In order to actuate the brake from the 5 front of the vehicle by means of a rod 3, on the outer end of shaft Z is mounted a second lever 5 with an end shaped as shown at Fig. 6, so as to engage and lock with a third and double ended lever 6 which is pivoted to the 10 rear portion H. The shortest and largest end of lever 6 is shaped so as to form a cam 7 arranged to lock the brake blocks N in position as shown at Fig. 7. The upper and free end of lever 6 is attached to the rod 3 for enabling the lever to be operated by hand. 15

When it is desired to throw the brake blocks N entirely out of action, the lever 12, shaped as shown at Figs. 1 and 8, mounted upon the bolt T, is turned over by hand and 20 its operative portion 13 is wedged between the shafts C and the under carriage D as shown at Fig. 8, thereby preventing any movement of the drawbar Q taking place. In its normal position the lever 12 rests upon 25 the shafts C as at Fig. 1.

In the above described apparatus the brake blocks N are applied to the wheels B by what may be termed a thrusting action which is obtained either by the backing of the horse 30 drawing the vehicle, or when the vehicle overruns the horse as in going down a hill, thereby causing the drawbar Q to move toward the rear of the vehicle and automatically apply the brake. The pulling action 35 for drawing the vehicle is utilized, in this instance, for applying the brake. The brake is locked in the "on" position by hand by means of rod 3 and lever 6, and in the "off" position by lever 12. When it is desired to 40 utilize the said pulling action for removing the brake blocks N from the periphery of wheels B, the said blocks and parts connected therewith are arranged at the rear of wheels B, and the drawbar Q and link R are 45 connected to the bar S as follows:—To the front portion K is fixed a bracket 8 to which is fulcrumed a slotted and double ended lever 5. To the lower end of lever 9 the link R is 50 connected and the upper end of the lever is slotted to permit of a pin 10 carried in bearings 11 formed for its reception in or on the rear end of bar S. The inner end of the drawbar Q and link R are at a suitable distance below the center pole G so as to permit 55 of the lever 9 working freely. The drawbar Q will also require to be curved or bent so as to bring its rear end to its proper working level. As the bar S draws the pin 10 forward, the slotted end of lever 9 is carried to 60 ward the front portion K and the link R and drawbar Q moved rearwards, thereby moving the brake blocks clear of wheels B. Should the vehicle overrun the horse the brake is automatically applied as above described.

The action of the apparatus is as follows:— 65 The various parts of the apparatus having been adjusted to their working positions with lever 12 resting upon the shafts C, and the brake blocks N clear of the peripheries of wheels B, on the horse backing or the vehicle 70 over running the horse, the drawbar Q will be moved to the rear of the vehicle carrying with it the cross piece O and brake blocks N and pressing the latter tightly against the wheels B. Simultaneously with this movement and by their connection with the cross piece O the levers 1, 5, will have been moved by bar 2 into the position for the ends of levers 5 and 6 to lock together when the rod 3 is pulled by hand, thereby moving the lever 6 80 into the position shown at Fig. 7 as previously described for keeping the brake blocks N against the peripheries of the wheels B. When it is required to release the lever 5 and blocks N, the rod 3 is moved by hand in the 85 opposite direction, thus changing the position of lever 6 to that shown at Fig. 6, and permitting the shaft Z to turn in its bearings for raising the lever 5, whenever the drawbar Q is drawn or moves toward the 90 front of the vehicle. The same action for moving the brake blocks N into contact with wheels B may be obtained by moving the rod 3 forward, thereby directly operating lever 6 and parts connected therewith. The 95 link R permits of the drawbar Q being actuated irrespective of the angle of the bar S, undercarriage D, and shafts C.

I claim:—

1. In brake actuating mechanism for vehicles, the combination of the wheels mounted upon axles, a sliding drawbar mounted in bearings on the undersurface of the vehicle between the wheels, a pendent bolt arranged to slide on the drawbar and to be adjustably fixed thereto by a hand wheel mounted upon the said bolt, a crosspiece having brake blocks fixed thereto, said crosspiece being mounted upon the pendent bolt so as to travel with the drawbar, and the means for 100 operating the drawbar as set forth.

2. In brake actuating mechanism for vehicles, the combination with body portion and rear wheels, of a sliding drawbar mounted in bearings under the body of the vehicle, a 115 bifurcated bar connected to the drawbar by a link, shafts attached to the forward and bifurcated ends of the said bar, brake blocks mounted upon a crosspiece and adjustably suspended from the drawbar, and the means described for fixing the cross piece to the drawbar so that the brake blocks and crosspiece will move therewith, as set forth.

3. In brake actuating mechanism for vehicles, the combination of the body portion 125 mounted upon wheels having a sliding drawbar attached thereto, a bifurcated sliding bar carried by bearings fixed to the undercar-

riage of the vehicle, and attached by a link to the said drawbar, shafts connected to the forward and bifurcated ends of said bar, a lever for arresting the movement of the drawbar, an adjustable slide mounted upon said drawbar and means for fixing it in position, a crossbar fixed to said slide and having brake blocks fixed to its outer ends, a shaft fixed to the rear portion of the vehicle and connected by a bar to the crosspiece and to a lever on said shaft having a second lever mounted on its outer end, adapted to engage with a cam lever fulcrumed to the rear portion of the vehicle, and a rod for operating the last named lever from the front of the vehicle as set forth.

5 10 15

4. In brake actuating mechanism for vehicles, the combination of the sliding drawbar carried in bearings on the undersurface of the vehicle, a bifurcated bar sliding in the undercarriage, a pin carried by said bar, a slotted lever fulcrumed to the front portion of the vehicle and interposed between the said sliding bar and drawbar, said lever engaging the pin at one end, and its opposite end being 20 25 connected by a link to the drawbar a crossbar having brake blocks fixed at its outer ends and means described for attaching the cross piece to the drawbar as set forth.
